BAILER UNLOADING RACK

James J. Santiago, Los Angeles, Calif., assignor
to Grant Oil Tool Company, Los Angeles, Calif.,
a corporation of California

Application September 4, 1945, Serial No. 614,155

3 Claims. (Cl. 166—19)

1

This invention has for its general object to facilitate the discharge or dumping of fluid charges from well bailers, in the operation of which the charge is taken into a bailed lowered to the bottom of the well, and is dumped by manipulation of the bailed parts after removal to the ground surface. More particularly, the invention relates to a novel bailed support or cradle adapted to receive or support a type of bailed having parts relatively movable to dump the charge, the function of the support cradle being to hold one such bailed part against movement during the fluid dumping manipulation of the other part.

As illustrative, the invention will be described with reference to a cradle-type support adapted to receive a bailed of the type and construction shown in my co-pending application Ser. No. 540,782, filed June 17, 1944, on Hydrostatic bailed, now abandoned. That type of bailed comprises a combination of parts or sections, one of which is rotatable relative to the other to dump the charge through an opening in the side of the bailed. One particular object of the invention is to adapt the supporting cradle for engagement with one of the bailed sections to hold the latter against rotation during rotative movement of the other section in the charge dumping operation.

In accordance with the invention, I have provided a bailed support which most desirably has the form of a cradle capable of supporting the bailed in an upright position, but preferably at a suitable inclination. Incorporated in the cradle structure is a holding means for restraining rotation of the engaging portion of the bailed. In the hereinafter described specific form adapted for cooperation with the type of bailed disclosed in my said co-pending application, such holding means may consist of a simple shoulder arrangement engageable against flattened surfaces on the bailed to arrest rotation, and adapted also to vertically support the bailed.

The various features and objects of the invention, as well as the details of a typical and preferred form, will be understood to better advantage from the following description of the accompanying drawing, in which:

Fig. 1 is a perspective view showing the bailed support;

Fig. 2 is a fragmentary sectional view illustrating a typical form of bailed inserted in the support; and

Fig. 3 is a cross-section on line 3—3 of Fig. 2. Referring first to Fig. 1, the support, generally indicated at 10, may have any suitable base or means for attachment to the derrick floor for

the purpose of securing the support in place. As illustrative, the structure is shown to comprise a base 11 having holes 12 for the reception of anchor screws or bolts. Extending vertically above the base is a suitable cradle support, shown typically as a pipe column 13 of sufficient height to accommodate the lower portion of the supported bailed above the floor or base. A cradle 14, open at one side as illustrated, is mounted on the column 13, preferably in an inclined position so that when received in the cradle, the bailed, generally indicated at 15 in Fig. 2, reposes at about the angular position illustrated. The cradle contains a pair of spaced oppositely positioned lugs 16, see Fig. 3, presenting upwardly facing shoulders 17 upon which the bailed body is rested as will now be described.

The bailed 15 may be of any suitable type and construction comprising a pair of relatively rotatable sections, one of which is receivable between and held against rotation by the lugs 16, while the second section is rotatable to dump the fluid charge. Typically, the bailed is shown to comprise a pair of tubular sections 18 and 19, the former of which comprises a pipe section 20 forming the charge-receiving chamber, and a sub 21 having a depending tubular extension 22 containing a dump opening 23. A frangible disc 24, received within extension 22, is seated upwardly 30 against the sub-contained shoulder 25.

The outer bailed body section 19 comprises a tube 26 threaded at 27 on the sub so as to be relatively rotatable, and containing an opening 28 into registration with which opening 23 is brought by relative rotation of the described inner body section 18, as by turning tool inserted within the recess 29. Opposite side surfaces of the lower portion of tube 26 are flattened at 30 for reception between the cradle lugs 16 and to form downwardly facing shoulders 31 which, as illustrated in Fig. 2, rest upon the cradle lug shoulder 17.

The bailed contains a tubular mandrel 32 carrying a combination disc breaker and ball check cage 33 containing the valve 34. The bottom tubular portion 35 of the mandrel may carry the usual ring, not shown, or have other details of construction immaterial to the present invention.

The bailed is operated in the usual manner by lowering it in the well until the lower portion 35 of the mandrel bottoms in the hole and continued downward movement of the bailed body (with its sections 18 and 19 positioned as in Fig. 2) impacts and breaks the disc 24 against the mandrel head 33. The well fluid and said charge then is taken up through the mandrel

past the valve 34 into chamber 36, the valve thereafter seating to retain the charge. The bailer then is removed from the well and placed in the cradle 14 as shown in Fig. 2, with the opening 28 at the open side of the cradle. It will be understood that the mandrel 32 may be dropped within the body to any location below its disc breaking position to permit access of the fluid in chamber 36 to the inner opening 23. By then rotating the inner body section 18, the outer section 19 being held against rotation between the cradle lugs 16, opening 23 is brought into registration with opening 28 to permit complete out flow of the charge from chamber 36. During the described fluid dumping operation, the bailer may be held against displacement out of the cradle by a pin 38 carried on chain 39 and inserted through opening 40 in the sides of the cradle.

I claim:

1. Apparatus for use in dumping a fluid charge from a well bailer having parts relatively rotatable to dump the charge, a floor-supported standard, a vertically inclined continuously open side cradle carried by said standard and adapted to receive and support the bailer in inclined position, and means forming within the cradle an open end recess adapted to receive and hold one of said bailer parts against movement relative to the other part, said means also presenting upwardly facing shoulders upon which the bailer is rested.

2. Apparatus for use in dumping a fluid charge from a well bailer having parts relatively rotatable to dump the charge, comprising a continu-

ously open side cradle adapted to vertically support the bailer in an upright position, means for engaging and holding one of the cradle-supported bailer parts against rotation relative to the other part, and releasable means for retaining the bailer in the cradle.

3. Apparatus for use in dumping a fluid charge from a well bailer having parts relatively rotatable to dump the charge, a floor-supported standard, a vertically inclined continuously open side cradle carried by said standard and adapted to receive and support the bailer in inclined position, means forming within the cradle an open end recess adapted to receive and hold one of said bailer parts against movement relative to the other part, said means also presenting upwardly facing shoulders upon which the bailer is rested, and a bailer retaining pin insertible across the cradle through the sides thereof.

JAMES J. SANTIAGO.
